HOUSING FOR A KEYBOARD, MUSICAL TONE GENERATOR AND ELECTRONIC AMPLIFIER OR SIMILAR ARTICLE

John Paul Arseneault, 25 Seely Drive, Downsview,
Ontario, Canada

Filed June 28, 1968, Ser. No. 12,550

Term of patent 14 years

Int. Cl. D17—01

U.S. Cl. D56—1

FIG. 1

FIG. 2

FIGURE 1 is a front, top and right side perspective view of a housing for a keyboard, musical tone generator and electronic amplifier or similar article, showing my new design; and

FIGURE 2 is a rear, bottom and left side perspective view thereof.

I claim:

The ornamental design for a housing for a keyboard, musical tone generator and electronic amplifier or similar article, as shown.
